[57] CLAIM

The ornamental design for a steam-fry waterless cooker, as shown and described.

DESCRIPTION

FIG. 1 is an exploded perspective view of my steam-fry waterless cooker, as seen from the left and slightly above.

FIG. 2 is an exploded perspective view of the same, as seen from the right and slightly below.
